UNITED STATES PATENT OFFICE.

JOSEPH B. STRAUSS, OF CHICAGO, ILLINOIS.

HOLDING-RACK FOR CHECKS.

SPECIFICATION forming part of Letters Patent No. 783,478, dated February 28, 1905.

Application filed August 20, 1904. Serial No. 221,573.

To all whom it may concern:

Be it known that I, JOSEPH B. STRAUSS, a citizen of the United States, residing at Chicago, in the county of Cook and State of Illinois, 5 have invented a certain new and useful Improvement in Holding-Racks for Checks, &c., of which the following is a specification.

My invention relates to holding-racks for checks and the like, and has for its object to 10 provide a new and improved device of this description.

My invention is illustrated in the accompanying drawings, wherein—

Figure 1 is a plan view of a device embodying my invention. Fig. 2 is a sectional view taken on line 2 2 of Fig. 1. Fig. 3 is an enlarged sectional view taken on line 3 3 of Fig. 2. Figs. 4 and 5 are views showing parts of the device before being assembled.

Like letters refer to like parts throughout the several figures.

The device herein shown is made of sheet metal; and it consists of a series of separated parts adapted to be assembled into a complete device. A series of pieces of sheet metal are cut the proper size and are bent into a cylindrical shape, so as to form the holding-pieces A. This holding-piece is open at the side, as shown at A', the opening being less in width than 25 the inside diameter of the holding part. The edges of the holding part are bent at an angle to the body portion, so as to project outwardly, as shown at A², thus providing each holding part with two substantially parallel projecting ribs or parts. These holding-pieces are provided at the top with laterally-projecting fastening-pieces A³ and at the bottom with 30 similar fastening-pieces A⁴. These holding-pieces are then inserted between the top and bottom plates C and D and are suitably spaced. A series of connecting-pieces B are inserted 35 between the holding-pieces. These connecting-pieces, as shown, are curved, so that when assembled a curved periphery is formed. Said connecting-pieces are provided with laterally-projecting ribs B', which engage the ribs A² on the holding-piece A, and the two sets of ribs may be soldered together, if desired. The 40 connecting-pieces B are provided at the top with lateral fastening-pieces B², which pref-

erably project inwardly, and at the bottom with similar fastening-pieces B³. When these fastening-pieces are used, they are riveted or otherwise fastened to the top and bottom C and D. The fastening-pieces A³ and A⁴ are 55 also similarly attached to the top and bottom, and thus the various parts are held in position. The top and bottom are connected together in any suitable manner—as, for example, by rods E. It is of course evident that 60 when the fastening-pieces are used it is unnecessary to solder the ribs A² and B' together. As shown in the drawings, the top and bottom pieces are provided with projecting parts C², D², and the attaching-pieces 65 A³ and A⁴ and B² and B³ are provided with holes into which these projections are received in assembling the parts. The parts are then held in position by the rods E. When these attaching parts are omitted, the parts are held 70 together in any other desired manner, as by means of solder. The ribs B' are preferably inclined inwardly, and the ribs A² are also slightly inclined, so that when in engagement a binding effect will be secured and the connecting-pieces B cannot be withdrawn laterally.

The top C is provided with openings which correspond in diameter to the inner diameter of the holding-pieces A. The bottom piece D 80 is provided with slots D', less in cross-sectional area than the holders A, so that the checks or other devices may rest on the bottom and be held in place and may yet be easily removed by inserting the finger in the opening D' and 85 moving it upward along the opening A'.

The device, if desired, may be rotatably mounted upon a base F by means of a rod F' passing through the base and through the bottom D. I have also shown the device provided with the pockets G and the handle H.

The device, as shown, is therefore made up of a series of elements, one set of said elements acting as holding parts, another set acting as connecting parts, said elements provided with 95 means for holding them in proper position and alignment and adapted to be assembled about a center.

I have described in detail a particular construction embodying my invention; but it is 100

of course evident that the parts may be varied without departing from the spirit thereof, and I therefore do not limit myself to the particular construction shown.

5 I claim—

1. A holding-rack for checks, &c., comprising a series of separate inflexible holding-pieces, a series of separate connecting-pieces between the rigidly-holding pieces, and means 10 for holding said several pieces in the proper relative position.

2. A holding-rack for checks, &c., comprising a series of holding-pieces each provided with a slot or opening extending from the top 15 to the bottom, a laterally-projecting rib on each side of said slot, a series of connecting-pieces between said holding-pieces each provided with laterally-projecting ribs adapted to engage the ribs of the holding-pieces, a top 20 and bottom piece between which said several pieces are received, and means for holding the pieces in proper position.

3. A holding-rack for checks, &c., comprising a series of cylindrical holding-pieces open 25 at the top and bottom and provided with a longitudinal slot, an engaging face on each side of said slot, a series of intermediate curved connecting-pieces spanning the space between the holding-pieces and provided with engaging

faces which coöperate with the engaging faces 30 on the holding-pieces, and a top and bottom piece between which said holding-pieces and connecting-pieces are clamped.

4. A holding-rack for checks, &c., comprising a series of holding-pieces bent into cylindrical form with their edges separated so as to form slots, said edges bent at an angle to the body of the holding-pieces so as to form angular engaging parts, a series of connecting-pieces between the holding-pieces provided 40 with angular projecting parts which engage the angular projecting parts on the holding-pieces, laterally-projecting fastening-pieces on the holding-pieces, and a top and bottom plate between which said pieces are received. 45

5. A holding-rack for checks, &c., comprising a series of separate holding-pieces, each having a slot extending throughout its length, a series of separate connecting-pieces between the holding-pieces, a top and bottom piece between 50 which the holding-pieces and connecting-pieces are received so as to be rigidly held against relative movement.

JOSEPH B. STRAUSS.
